WARDROBE SUITCASE

Julius Ritter, Jr., Racine, Wis., assignor to
Hartmann Trunk Company, Racine, Wis., a corporation of Wisconsin

Application November 18, 1938; Serial No. 241,113

1. Claim. (Cl. 190—41)

This invention relates to improvements in wardrobe suitcases. Heretofore, in wardrobe suitcases wherein there are U-shaped garment folding and supporting frames hingedly connected adjacent the hinge connection for the cover, the side arms of the folding frame have been of fixed length so that the transverse garment folding bar is always positioned at the same place adjacent the free edge of the cover when the frame is positioned in said cover. This type of folding frame is usually cooperable with one or more hanger rods removably positionable adjacent the hinge connection for the frame and in spaced parallel relationship with respect to the folding bar at the swinging end of the frame. With this arrangement the garments are folded twice to hang in four adjacent layers. If all dresses were of the same length and if no changes in length were made from year to year it would be a relatively simple matter to properly support garments on this type of wardrobe fixture. However, women are of varying height and the length of their dresses varies in accordance with their height and in accordance with the dictates of fashion. For this reason it frequently happens with folding frames of the ordinary type, that the free ends of a short dress will barely hang over the transverse bar at the free end of the frame instead of extending down adjacent the hinged end of said frame. As a result, when the frame is moved these short free ends are likely to slip over the transverse bar and lie in crumpled condition in the cover behind the folding frame.

It is therefore a general object of the present invention to provide a construction wherein the distance between the transverse folding bar and the hinged end of the garment folding frame may be varied to suit requirements whereby either long or short dresses may be supported properly with the free ends hanging a sufficient distance below the transverse folding bar to prevent their slipping off.

A further object of the invention is to provide in a wardrobe suitcase a garment folding fixture so constructed that when short garments are packed there is more room between the folding bar and the front wall of the cover to accommodate heavy material without undesirable squeezing of said material between the folding bar and the front wall of the cover, said additional space also being available for other small articles or garments when not taken up by the garments on the folding frame.

A more specific object of the invention is to

provide a construction wherein the object is preferably accomplished by the use of telescoping side arms for the garment folding frame.

Other objects of the invention are to provide a construction as above described including stop means for limiting the maximum length of the frame; including means for positively locking the frame in any position of adjustment; and including means for facilitating the adjustment operation.

With the above and other objects in view the invention consists of the improved wardrobe suitcase and all its parts and combinations as set forth in the claim and all equivalents thereof.

In the accompanying drawing, illustrating one complete embodiment of the preferred form of the invention, wherein the same reference numerals designate the same parts in all of the views:

Fig. 1 is a vertical sectional view through the main body of the suitcase showing the cover in raised position; the dot and dash lines indicating an adjusted position of the garment folding frame;

Fig. 2 is a sectional view taken on line 2—2 of Fig. 1;

Fig. 3 is a fragmentary detailed view of one of the side arms of the folding frame showing the frame in its shortest position of adjustment and showing how the frame may be extended;

Fig. 4 is a similar view showing the side arm locked in fully extended position; and

Fig. 5 is a sectional view taken on line 5—5 of Fig. 4.

Referring more particularly to the drawing, the numeral 8 designates the main body portion of a suitcase, said main body portion having a cover 9 hingedly connected thereto. The cover comprises side walls 10 and 11, a front wall 12 and a back wall 13. Stays 14 of the usual type may be employed to hold the cover in raised position.

Pivotedly connected to the sides 10 and 11 of the cover adjacent the hinge connection for the suitcase are the side arms 15 and 16 of a garment folding frame. These side arms may be pivotally connected through the medium of attaching brackets as described in co-pending application of Joseph Kiefer, Serial No. 232,981, filed October 3, 1938, or they may be pivoted on rivets extending through the walls of the cover. It is possible that the side arms 15 and 16 be hinged in the main body portion of the case to swing into the cover when the case is closed. Connected to the

free ends of the arms 15 and 16 is a transverse garment folding bar 17.

One or more garment hangers 18 may be removably supported in a carriage 19 and said carriage may be removably supported in the suitcase in the manner disclosed in the Kiefer application, Serial No. 232,981, above referred to or may be supported in any other manner. The garment hanger members 18 may also be removably positionable adjacent the hinge connection of the garment folding frame in any other well known manner. It is contemplated that the garment hanger member include either hangers of the bar type as indicated at 18 or the ordinary coat hanger type.

Each of the side arms 15 and 16 is of identical construction, except that one is a right-hand fitting and the other a left-hand fitting, and each comprises an inner strip of material 20 having a flattened tubular part 21 extending therefrom and secured thereto by a rivet 21'. One side of the flattened tubular part 21 is formed with an elongated opening 22 and within the tubular portion 21 an outer side arm part 23 is slidable as illustrated in Figs. 3 and 4. The inner end of the part 23 is formed with spaced apertures 24 which register with the elongated opening 22. Pivoted to the rivet 21' to swing in the manner shown in Fig. 3 is a latching strip 25 carrying a latching pin 26 near its free end. The latching pin 26 is adapted to enter a selected one of the apertures 24 to lock the part 23 in a desired position of adjustment as shown in Figs. 4 and 5. A stop pin 27 is adapted to engage the inner end of the elongated opening 22 to limit the inward movement of the part 23 and to engage the outer end of the elongated opening 22 to limit the outward movement and to prevent the parts of the side arms from being pulled entirely apart.

In order to adjust the garment folding frame to a desired length the latching strips 25 on both side arms are pulled out and swung to the position of Fig. 3. Next the transverse folding bar is pulled or pushed to a desired position and then the latching strips 25 are swung back to the position of Fig. 4 and the pins 26 are caused to enter selected apertures 24 to lock the side arms in a desired position of adjustment.

In packing a garment in the suitcase one of the bars 18 is removed and the garment is folded thereover. Next the bar is inserted into the suitcase while the garment folding frame is in the lowered dot and dash line position of Fig. 2. The frame is then swung upwardly into the cover as shown in Fig. 2, causing the garment to be folded over the transverse bar 17 as at 28. The free ends 29 of the garment will then hang down toward the hinged end of the garment folding frame as shown in Fig. 2. If, however, the garment folding frame were of a fixed length equal to the dot and dash line position of Fig. 1, as is standard practice, and if a very short dress were being carried, the fold line 28 of the garment might be so close to the free ends 29 that said

free ends would be in danger of slipping over the rear side of the folding bar 17 to lie in rumpled condition behind the folding frame in the cover. Therefore, with the present invention, when short garments are being carried, the folding frame is adjusted to a shortened position as shown in full lines in Fig. 2, so that the free ends 29 will hang downwardly a sufficient distance to prevent their slipping off of the transverse bar 17.

The present construction is also useful in that the distance between the garment folding bar 17 and the front wall 12 of the cover may be varied to allow more room for heavy material. With ordinary constructions there is a relatively small amount of space between the folding bar 17 and the front wall 12 of the cover and no adjustment is possible. As a result when heavy material is being packed it is frequently squeezed between the folding bar 17 and the wall 12. The construction is further desirable because when the folding frame is adjusted to its shortened position, as shown in full lines of Fig. 2, there is a substantial amount of space between the transverse bar 17 and the front wall 12 of the cover in which small articles such as stockings, handkerchiefs or the like may be packed, to be held in place by the retaining curtain 30 when the latter is hooked on to the hook 31.

While the construction has particular utility in connection with a garment folding frame for use in cooperation with garment hangers such as the hangers 18, it also has utility in connection with garment folding frames used alone and it is obviously not essential that the garment folding frame be pivoted adjacent the hinge connection for the case as the invention has utility in connection with frames swingable upwardly adjacent the front wall of the main body of the case.

Various other changes and modifications may be made without departing from the spirit of the invention and all of such changes are contemplated as may come within the scope of the claim.

What I claim is:

In a swingable garment folding frame having spaced side arms, a transverse garment folding bar connecting said side arms, each side arm being formed of telescopic sections, one of said sections of each side arm having a tubular part formed with an elongated slot therein, and a second section of each side arm having a portion provided with spaced apertures which is slideable in said tubular part of the first section, the apertures being exposed through said elongated slot, and an elongated yielding latching strip connected to said first section and having a latching pin projecting therefrom which is engageable through the elongated slot of the first section with a selected aperture of the second section to lock the sections in a selected position of adjustment, said latching strip when in locking position covering the elongated slot of the tubular part of the first section.
